UNITED STATES PATENT OFFICE.

JAMES PATON, OF CLEVELAND, OHIO.

MACHINE FOR GALVANIZING SHEET OR PLATE METAL.

SPECIFICATION forming part of Letters Patent No. 414,951, dated November 12, 1889.

Application filed March 27, 1889. Serial No. 305,025. (No model.)

To all whom it may concern:

Be it known that I, JAMES PATON, a resident of Cleveland, in the county of Cuyahoga and State of Ohio, and a citizen of the United States, have invented a certain new and useful Improvement in Galvanizing-Machines for Sheet or Plate Metal; and I do hereby declare the following to be a full, clear, and complete description thereof.

10 My invention relates to a machine or apparatus for galvanizing sheet or plate metal; and the improvement consists in the application of a skimming device in connection therewith, the purpose of which is to free the 15 surface of the molten zinc or tin from the oxide and impurities thereof at that part where the plates are drawn from out the molten metal.

That the invention may be fully seen and 20 understood, reference will be had to the following specification and accompanying drawings, in which—

Figure 1 is a vertical longitudinal section of a galvanizing pot or vat provided with the 25 improvement above referred to. Fig. 2 is a partial plan view of the same. Fig. 3 is an end view of said pot or vat with the improvements attached; and Fig. 4 is a transverse vertical section of the same, looking toward 30 the end and illustrated in Fig. 2.

Like letters of reference refer to like parts in the drawings and specification.

In all the figures the pot or vat A is shown as detached from the furnace into which it is 35 set or by which it is surrounded, for the purpose of melting the zinc, tin, lead, or other suitable metal placed thereon, and to keep said metal in a proper molten state for coating the immersed sheet or plate of metal. It is 40 well known that in the galvanizing process of plate or sheet metal sal-ammoniac is required as an agent in the process. The sal-ammoniac thrown into the vat will remain in form of a liquid layer on top of the molten zinc.

45 Thus all the sheet or plate metal has to pass through said layer of sal-ammoniac before it can be immersed into the zinc bath. However, on withdrawing the thus-coated sheet of metal it is of vital importance that the 50 face of the molten zinc should be free from all deposits and impurities, so that nothing

can adhere to said sheet but the clear zinc, which, when left undisturbed while cooling, will greatly improve the appearance of the sheet by a glossy and pronounced crystallization with a more uniform coating by passing out from the clean metal. 55

To obtain a clear surface of zinc of the required extent or space through which the sheets are drawn from the zinc bath, a skimming device of the following construction is employed: The devices substantially consist of a pair of metallic rolls B and B' and suitable bearings, guides, and gearings for suspending, adjusting, and revolving said rolls 60 in the manner as hereinafter set forth. The bearings of said rolls B B' are seen at a b, Figs. 1 and 2, which bearings project inwardly from the lower part c of the slide C. Both the lower part c and upper part c' are united 65 by means of bolts or rivets and thus form the slide C, which is located between the guides D D. To the angle-plates E E, at either end of the vat A, is bolted the bottom plate F of 70 said guides D D, as seen in Figs. 2 and 3. 75 The angle-plate E, as well as the bottom plates F, have elongated holes in the face sides thereof, as seen at g, so as to enable proper adjustment of the guides D D in relation to the rolls B B'. Each of said slides is provided 80 with a lug d, into which is threaded a spindle G, Figs. 1 and 2. The spindles rest upon the plate F, and when turned carry the rolls B B' either up or down, as seen in Figs. 1 and 4. The rotation of the rolls is caused by the 85 gearing H J and I I from the gear H, motion being imparted to the gears I I by means of the intermediate gear J—that is, if the gear H is rotated in direction of the arrow, then the gears I I will be turned so as to rotate 90 the rolls B B' in opposite direction. The spindle K, carrying the gear H, may either be turned by hand or by means of a crank, or motive power may be applied on a pulley secured to said spindle. The intermediate gear 95 J allows the lowering of the rolls B B' more or less into the vat A, while the spindle K, with the gear H, may yet be far enough above the vat to enable the turning of said spindle. The raising or lowering of the rolls B B' is 100 done by means of the spindles G G, as above stated, which adjustment is necessary accord-

- ing to the variations of the level of the molten zinc within the vat. When in operation, said rolls should be immersed in the metal to about the extent as indicated in Fig. 4, where-
5 in *e* denotes the level of the zinc, and *f* the layer of sal-ammoniac. In rotating the rolls in that position and in the direction as above stated all the impurities which may either be expelled in melting the zinc or may have
10 been in combination with the sal-ammoniac rise to the surface between the rolls and are taken up by said revolving rolls and carried by the same over to the opposite side of said rolls, thus effecting between the rolls a space
15 of molten zinc, the surface of which is entirely freed from all oxides or other impurities.
- The sheets or plates can be sunk into the molten metal from either side of the vat on the outside of the rolls by means of suitable
20 guides and hooks, the immersed sheets being then pushed under and lifted when between the rolls for withdrawal from the molten zinc, during which time the rolls are continuously revolved for the purpose, as above stated.
- 25 The bearings of the rolls *I* *I* are within the heated metal, and are thus exposed to the action of the zinc, which will corrode or disintegrate the slide *C* at that part long before the upper parts become worn out. Thus said
30 slide *C* is made of two parts *c* and *c'*, to allow of keeping said slide *C* in repair at considerably less expense than if the said slide were made of one piece; hence the lower part of the slide may be withdrawn and a new one
35 substituted without renewing the upper part

thereof. When the operation of the vat is suspended, the rolls are lifted from out the zinc, which may be done by turning the crank-handle *L* of the screws *G* *G*; or the slide and rolls may be entirely lifted out of the guides *D* ⁴⁰ *D*, in which case the holes *g'* in the slides *C* *C* permit the use of a hook or withdrawal attachments for such renewal.

What I claim as my invention, and desire to secure by Letters Patent, is—⁴⁵

1. In combination, a vat, slides *C*, held by suitable guides, rolls having their bearings in said slides, and threaded spindles *G*, in connection with the slides for adjusting the same vertically, and means for driving the ⁵⁰ rolls, also carried by the slides and adjustable therewith, substantially as described.

2. In combination, a vat, slides supported thereon in guides, rolls supported in bearings carried by said slides, a lug on each slide having a screw-threaded opening, and threaded spindles *G*, passing through said lugs for adjusting the rolls vertically, with means for operating the rolls, substantially as described.⁵⁵

3. In combination with a vat, the slide consisting of two parts, the lower part being provided with bearings for rolls, gearing supported by the slides for driving the rolls, and means for adjusting the slides vertically.⁶⁰

In testimony whereof I affix my signature in presence of two witnesses.

JAMES PATON.
